Falls, Pa., a corporation of Pennsylvania

Application March 6, 1935, Serial No. 9,567

15 Claims.

(Cl. 1—48)

My invention relates to a fastening apparatus of the type in which the fasteners are fed from a magazine successively as used, and to a novel method of manipulating the fasteners in preparation for use.

I am aware that magazine fasteners have been known heretofore, including a magazine for a plurality of fasteners in the form of staples connected together forming a unitary strip, but such fasteners, while portable, are more or less restricted in their application. In accordance with my invention, I provide a device which is generally hammer-like in form, having a head provided with a magazine for strips of staples as aforesaid, and means for feeding the strip by placing the staples thereof successively in position for use.

In the strip staple fasteners known heretofore, the staples are detached successively from the strip by the shearing action of a driving plunger. I have invented a novel method of manipulating the staples of a strip prior to driving, which does not depend on any shearing action. In accordance with the invention, I bend the staples successively from the strip to produce an incipient fracture which is adapted to be completed as the staple is driven.

For a complete understanding of the invention, reference is made to the accompanying drawings illustrating a present preferred embodiment with certain modifications, although it will be understood that the invention may be incorporated in forms other than those shown, and practiced otherwise than specifically as described herein, within the scope of my broader claims. In the drawings:

Figure 1 is a side elevation of one form of fastening apparatus in accordance with my invention showing a staple in position for driving;

Figure 2 is a similar view showing the manner of bending the staple into position for driving;

Figure 3 is a partial longitudinal section along the plane containing the axes of the head and handle of the hammer showing the manner of introducing the strip of staples to the magazine;

Figure 4 is a sectional view along the line IV—IV of Figure 1;

Figure 5 is a view similar to Figure 3, to some-what enlarged scale, showing the first step of the operation of feeding and bending the staple from a strip in the magazine;

Figure 6 is a similar view showing the staple after it has been bent into position for driving;

Figure 7 is a similar view of the final stage after

the feeder has been withdrawn, showing the means for holding the strip against retraction;

Figure 8 is a sectional view through the head and handle of a modified form of the apparatus;

Figure 9 is a sectional view along the line 5 IX—IX of Figure 8; the line VIII—VIII of Figure 9 indicates the plane on which the section through the hammer head shown in Figure 8 is taken;

Figure 10 is a partial sectional view along the 10 line X—X of Figure 9, the hammer head appearing in elevation;

Figure 11 is a similar view along the line XI—XI of Figure 9;

Figure 12 is a bottom view of a guide bar having holding detents thereon for securing the staple strip against retraction;

Figure 13 is a partial view similar to Figure 8 showing the first step in the operation of bending a staple into position for driving;

Figure 14 is a similar view showing a further stage of the operation;

Figure 15 is a similar view showing the staple after it has been finally positioned for driving;

Figure 16 is a view similar to Figure 8 showing 25 a preferred form of the invention;

Figure 17 is a side elevation, partly broken away, of the head of the device of Figure 16;

Figure 18 is a plan view of a handle socket on which the head is pivotally mounted;

Figure 19 is a sectional view along the line 30 XIX—XIX of Figure 18;

Figure 20 is a sectional view along the line XX—XX of Figure 18;

Figure 21 is an elevation of a cutter bar forming part of the device of Figure 16;

Figure 22 is a side view thereof; and

Figure 23 is an elevation of the feeder of the device of Figure 16.

Referring now in detail to the drawings and, for the present, to Figures 1 through 7, the invention comprises a hammer head 10 pivotally mounted on a handle socket 11 by means of a pin 12. The socket is provided with a handle 13 by which the device may be held in use.

The socket has shoulders 14 and the portions 15 of the head extending over the ends of the socket are beveled as at 16 whereby the head is rockable on the pin 12 to either of two extreme positions (see Figures 1 and 2).

The head has an outer longitudinal slot 17. A guide block 18 is mounted in the slot 17 but spaced from the bottom thereof, adjacent one end of the head, forming a chamber or magazine 19 for the reception of a strip of staples indicated 55

at 20. The other end of the slot 17 is closed by a head plate 21. The distance between the plate 21 and the end of the block 18 is sufficient to receive a strip of staples which may be bent slightly if necessary for insertion therein.

A holding detent 22 in the form of a leaf spring is attached at one end to the block 18 and has its free end suitably shaped to engage the strip 20 as it is advanced by means to be described shortly, 10 and hold it against retraction. A heel 23 is formed on the block 18 whereby the head may be tilted, as shown in Figure 2, by pressing the heel against any rigid surface.

The head 10 has an inner longitudinal slot 24 into which the projecting end of the socket 11 extends. A feeder bar 25 is reciprocable in the slot 24 in engagement with the end of the socket 11 indicated at 26. One end of the bar 25 is slideable by means of a slot 27 on a pin 28 extending 20 across the slot 24. A spring 29 pinned to the bar 25 and anchored to the head 10 adjacent the plate 21 tends to retract the bar to the position shown in Figure 1.

The bar 25 has a finger 30 extending at substantially right angles therefrom into engagement with a cam surface 32 in the socket 11 whereby, when the head 10 is tilted as shown in Figure 2, the free end of the bar 25 is pressed toward the bottom of the slot 24. The free end 30 of the bar 25 is formed into a finger 33 which is adapted to wipe around the arcuate end 34 of the web 35 between the slots 17 and 24. In so doing, the finger 33 is effective to advance the strip 28 for a distance equal to the width of one 35 staple, and bend the end staple about the inner edge of the block 18. The manner in which this result is effected will now be explained in detail.

As before stated, the strip 20 is inserted into the slot 17 between the plate 21 and the end of the block 18. The strip is then advanced through the magazine chamber 19 until the first staple on the strip overhangs the rounded end portion 34 of the web 35 as shown in Figure 5. This, of course, causes the spring detent 22 to be deflected 45 against the block 18. If the head 10 is then tilted as shown in Figure 2 by pressing the heel 23 against a rigid surface, the finger 30 cooperating with the cam surface 32, aided by the action of the end 26 of the socket 11 on the body portion 50 of the bar 25, will force the bar toward the bottom of the slot 24. The rounding of the web 35, as shown at 34, causes the bar to move slightly in longitudinal direction. This movement is permitted by the slot 27 and the spring 29. The 55 result is that the first staple on the strip is bent around against the end of the block 18 and, as an incident of the bending, an incipient fracture between the first staple and the remainder of the strip is formed. The bent staple, however, 60 is not entirely detached from the strip but is held in position for driving.

The pressure on the heel 23 is then released and the spring 29 restores the head to its original position. The finger 33 rides downwardly 65 over the second staple in the strip. The strip itself is held against retraction by the detent 22. The device is then in the condition illustrated in Figure 1, viz, with the first staple in position for driving. When the first staple is driven by a swing of the hammer, the slight remaining connection between it and the strip is immediately broken. The head 10 may then be reversed to strike a blow on the staple with the plate 21 to 70 complete the driving thereof, if desired. The device may then be operated in the manner de-

scribed to position the second staple for driving, merely by again pushing on the handle 13 while the heel 23 engages a rigid surface.

A modified form of the invention is illustrated in Figures 8 through 15. In this form of the invention, a head 40 has a longitudinal slot 41 extending from end to end thereof. A guide bar 42 of substantially T-section is secured in the slot 41. A hollow tubular handle 43 is secured to the head, preferably being slotted to receive the latter.

It will be apparent from Figure 9 that the guide bar 42 is so arranged relative to the slot 41 in the head 40 as to provide a passage of inverted U-shape extending the length of the head. A 15 staple strip 44 can thus be inserted in the right-hand end of the head, as viewed in Figure 8, and advanced toward the other end. The guide bar 42 is provided with holding detents 45 (see Figs. 8 and 12) similar to the detent 22 of the 20 device already described. The detents 45 engage the points of successive staples on the strip and prevent retraction of the strip after a feeding movement thereof by means which will now be described.

The left-hand end of the hammer head 40 is also slotted to receive a bending slide 46. The outer end of the slide 46 is in the form of a hook 47 adapted to engage the first staple of a strip and bend it around the end of the head so that 30 it bridges the slot in which the slide 46 is mounted. Movement of the slide 46 is controlled by notches 48 and 49 and a tooth 50 therebetween formed on one edge thereof, cooperating with a pin 51 extending through the head.

The inner end of the slide 46 extends within the tubular handle 43 and is there pivotally connected to an operating lever 52 pivoted in the handle at 53. The lever has a handle grip 54 extending outwardly of the handle through a slot 55 therein and is normally maintained in illustrated position by a leaf spring 56 carried on a plug 57 which closes the end of the handle 43 spaced from the head 40. A compression spring 58 abuts against the slide 46 adjacent the inner end thereof and the handle 43.

A feeding slide 59 is disposed in the slot 41 in the head 40 for reciprocation therein and is pivoted to the inner end of the slide 46. The free end of the slide 59 is bent inwardly to engage successive staples in the strip and push the latter forward step by step.

The operation of the device shown in Figures 8 through 15 will now be described with particular reference to Figures 13 through 15 illustrated in the various stages of the operation.

The staple strip 44 is first inserted in the slot 41 in the manner indicated in Figure 9, from the right-hand end thereof as viewed in Figure 8. The strip is advanced to the position shown in Figure 8 and is held there by the detents 45 against retraction. The device is then ready for use.

To position the first staple of the strip for driving, it is only necessary to depress the handle 65 grip 54 by manually squeezing it into the handle 43. The first result of this operation, as shown in Figure 13, is that the hook 37 engages the middle portion of the first staple of the strip, as the slide 46 is retracted due to squeezing of the lever 52. The slide 59 is also slightly retracted, as shown in Figure 13, the strip being held in position by the detents 45.

As the swinging movement of the lever 52 continues, the tooth 50 on the inner edge of the slide 75

46 engages the pin 51. Since the slide 59, which is pivotally connected to the slide 46, is in engagement with the flange of the guide bar 42, the slide 46 tends to swing counterclockwise, against the force exerted by the spring 58, so that the tooth 50 will clear the pin 51. The early stage of this movement is illustrated in Figure 14. The angular movement of the slide 46 tends to pull the first staple of the strip down over the end of the head 40 so that it bridges the end of the slot on which the slide 46 is mounted. The feeding slide 59, of course, is retracted to the same extent as the bending slide 46.

Continued movement of the lever 52 swings the slide 46 so that the tooth 50 clears the pin 51 as aforesaid. This permits the hook 47 on the end of the slide to clear the bent-over staple, whereupon the spring 58 forces the slide 46 back toward the staple strip 44. The first staple is then in position for driving, which may be accomplished by a swing of the hammer. It will be noted that in the fully actuated position of the lever 52 indicated in Figure 15, the feeding slide 59 is in line with one staple and will have to travel almost the full distance between adjacent staples before it will engage the edge of the next staple in advance to cause forward movement of the strip. On release of the handle grip 54, therefore, the spring 56 will cause reverse movement of the lever 52, whereupon the slide 46 will move to the left and, because of the cam action of the tooth 50 on the pin 51, will swing away from the head 40.

By the time the end of the feeding slide 59 engages the staple adjacent that opposite which the end of the slide was disposed in the extreme inward position thereof, the hook 47 of the slide 46 will have moved over the end of the strip as shown in Figure 8. Further resetting movement of the lever 52 causes the staple strip 44 to be advanced by the feeding slide 59 to the initial position of Figure 8. The device is then ready for a repetition of the staple bending and driving operations.

It will be apparent that the device of Figures 8 through 15 operates on the same principle as that of Figures 1 through 7, since the staples are bent successively from the strip in which they are supplied, to cause an incipient fracture therebetween whereby, on driving the staple, it is readily detached from the strip.

The preferred form of the invention is illustrated in Figures 16 through 23. This form of the invention is more closely similar to that of Figures 1 through 7 than to that of Figures 8 through 15. In this form of the invention, a head 65 has a slot 66 extending longitudinally thereof, and projections or ears 67 by which the head is pivotally mounted on a handle socket 68 by a through pin 69. The ends of the ears 67 are beveled at 70 for cooperation with shoulders 71 on the socket 68. The head 65 is thus tiltable on the socket to either of two extreme positions. A set screw 72 secures the pin 69 in position and a handle 73 is secured in the socket 68 by a pin 74.

A guide bar 75 is disposed in the slot 66, being secured to the head by rivets 76. As shown best in Figures 21 and 22, the guide bar has a T-section somewhat similar to that of the bar 42 of Figures 8 through 15, whereby a staple strip 77 may be guided through the slot 66. The guide bar has holding detents 78 similar in function to those shown at 22 and 45.

A feeder bar 79 has one end disposed between the guide bar 75 and the end of the socket 68 and

is yieldingly held in that position by a spring 80. The feeder bar has a finger 81 extending at substantially right angles thereto. The finger 81 is provided with gudgeons 82 adapted to slide on the flanges 83 of a slot 84 formed in one side of the socket 68. Portions of the flanges 83 are formed integral with the socket and the remaining portions thereof are formed on an insert 85 secured in position by a rivet 86.

The feeder 79 also has a finger 87, the function of which will be obvious from the previous description of Figure 1.

The operation of the preferred form of the invention disclosed in Figures 16 to 23, inclusive, is quite similar to that of the form disclosed in Figure 1. A clip of staples or the like is first fed to the magazine in the head and pushed forwardly through the magazine to the point where the first staple will be engaged by the finger 87 upon effecting relative movement between the head and the finger. The handle 73 is then seized by the user and the driving end of the hammer pushed against a fixed surface. The driving end is suitably shaped at 88 for this purpose. It is also provided with a hardened insert 89 over which the staple strip 77 is adapted to slide. When the driving end is pushed against a fixed surface the head 65 will be tilted clockwise about the pivot pin 69 as shown in Figure 16. This tilting of the head relative to the handle 73 causes the finger 87 to advance forwardly and upwardly and engage the first staple of the strip and pull it upwardly. As the finger 87 moves forwardly past the extreme end of the guide bar 75 it moves upwardly therearound and bends the first staple around the hardened insert in the foremost portion of the head so as to bring it into position on the driving end of the hammer. The second staple on the strip by that time has been advanced into the position in which the first staple is shown in Figure 16 and the strip is then held in that position by the detents 78. The bending of the staple in the aforesaid manner causes an incipient fracture between the staple and the strip on the connecting portion extending between adjacent staples so as to facilitate detachment of the staple from the strip when the staple is driven. If the pressure on the point 88 of the hammer head is released after the staple is fed forward in the manner above described, the spring 80 will draw the head and the feed bar 79 back into the positions illustrated in Figure 16. The finger 87 will then be in a position to engage, feed and bend the second staple in the strip on a successive tilting of the hammer head. Driving of the staple is accomplished by a swing of the hammer and the operations set forth above may then be repeated as often as desired. It will be understood from the above description that at the time that the driving operation is performed, the staple being driven has its prongs or legs extending longitudinally of the hammer head and at an angle of approximately 90° from the position occupied by the remaining staples in the strip. A hardened insert 90 is disposed in the end of the head opposite that on which the staple feeding mechanism is mounted, whereby staples which are not initially firmly driven into position by the initial driving action may be firmly driven into the work.

It will be apparent from the foregoing description that the method and apparatus of my invention make it possible to drive fastening devices, such as staples, at a much greater rate than would be possible with hand feeding. The limi-

- tations of previous types of automatic feed machines, furthermore, are entirely overcome and the desirable features thereof incorporated in a small hand tool which can be easily carried to any point of use and used in any position. The particular advantage of the invention over previous stapling machines, of course, is that the latter require that the work be placed in the machine. This is impossible in the case, for example, of nailing posters to a wall. Since my invention provides a stapling machine which can be moved bodily to the work, specifically in the form of a hammer, it will be obvious that an entirely new field for automatic fastening devices is created.
15. The advantage of bending the staple being driven from the strip in the magazine is two-fold. In the first place, it facilitates separation of the driven staple from the strip and in the second, permits the strip to be fed through a magazine extending longitudinally of the head, thus utilizing the conventional hammer design or outline.
- Although I have illustrated and described herein but one preferred embodiment of the invention and the method of practicing it, with certain modifications, it will be understood that many changes may be made in the method and apparatus described without departing from the spirit of the invention or the scope of the appended claims.
30. I claim:
1. Fastening apparatus comprising a handle, a head mounted thereon, a magazine in the head adapted to receive a staple strip, and means including an actuating bar for advancing the staple strip and bending staples successively therefrom to be driven by said head.
  2. Apparatus for fastening comprising a handle, a magazine for strip staples having a head adjacent the discharge end thereof, said magazine and head being mounted on said handle and means including an actuating bar for advancing a staple strip through said magazine and bending the staples thereon successively around said head in position to be driven thereby.
  45. 3. An automatic feed stapling hammer comprising a handle, a head mounted thereon, a staple strip magazine formed in said head, and means including an actuating bar movably mounted in the head for advancing the strip in said magazine and bending the staples thereof successively relative to the main body of the strip, and into position in which they are adapted to be driven by said head.
  4. A stapling hammer comprising a handle, a head tiltably mounted on the handle, a strip staple magazine in the head, and means including an actuating bar in the head actuated by tilting thereof on the handle for advancing the staple strip and bending the staples thereof successively into a position in which they are adapted to be driven by said head.
  55. 5. The apparatus defined by claim 4 characterized by means for holding the strip against reverse movement between feeding operations.
  65. 6. In a stapling hammer, a handle, a head mounted thereon, a magazine in said head for a staple strip, and means including an actuating bar operable to bend the strip successively between staples to cause a partial fracture between the staple and the rest of the strip.
  70. 7. A fastening hammer comprising a handle, a head mounted thereon, means in the head for

guiding a connected series of fasteners therethrough, and a finger mounted in the head adapted to successively engage and bend the fasteners from the series into driving position out of line with the series, the finger and head being movable relative to each other to bring the finger into operative engagement with the fingers. 5

8. A fastening hammer comprising a handle, a head pivotally mounted thereon, means in the head for guiding a connected series of fasteners therethrough, and a finger mounted in the head and operable by pivotal movement of the head on the handle for advancing and bending said fasteners successively to driving position. 10

9. A stapling hammer comprising a handle, a head mounted thereon, a magazine in said head for strip staples, means in the magazine for guiding a staple strip therethrough, and a finger reciprocably and pivotally mounted in the head and so arranged relative to said head and said magazine that relative pivotal movement between the head and said finger causes said finger to engage and successively advance the strip through the magazine and bend the staples contained therein to driving position at a substantial angle to the 20 strip. 25

10. The apparatus defined by claim 9 characterized by said head being pivotally mounted on the handle.

11. A stapling hammer comprising a head, a 30 magazine formed therein for strip fasteners, means in the magazine for guiding a strip therethrough, a handle on which said head is pivoted, and a feeder bar slidably in said head and adapted to be actuated by pivotal movement between the 35 head and handle to effect feeding and bending of the fastener strip.

12. A stapling device comprising a head, a magazine therein for strip staples, means for holding the strip against reverse movement, a 40 feeder bar slidable and rockable in said head for feeding the strip and bending staples successively therefrom about one end of the head, and manually operable means for actuating said bar.

13. A stapling device comprising a handle, a 45 head rigidly mounted on said handle, a magazine in said head for strip staples, means for holding the strip against reverse movement, a feeder bar slidable and rockable in said head for feeding the strip and bending staples successively 50 therefrom about one end of the head, and manually operable means including a member movably mounted in said handle for actuating said bar.

14. A stapling device comprising a handle, a 55 head mounted thereon, a magazine in said head for a staple strip, and means including an actuating bar movably mounted in the head and arranged to engage successively and individually the staples and bend them from the strip into a position at an angle to the strip for driving, said bending action being caused by relative movement between the actuating bar and the head. 60

15. Fastening apparatus comprising a head, a 65 magazine in the head adapted to receive a staple strip, and means including an actuating bar for advancing the staple strip in step by step fashion and for bending staples successively therefrom into position in which they are adapted to be driven by said head. 70
